Available from internet, URL: <https://www.uline.ca/Product/Detail/H-4976/Safety-Guards-Barriers/Safety-Railing-Steel-4> (Year: 2020).*Primary Examiner — George A Bugg*Assistant Examiner* — Tamara L Hahn(74) *Attorney, Agent, or Firm* — Luedeka Neely Group, P.C.(57) **CLAIM**

The ornamental design for an extendable gate for a trolley, as shown and described.

DESCRIPTION

FIG. 1 is a front upper perspective view of an extendable gate for a trolley showing our new design;

FIG. 2 is a left side view of thereof;

FIG. 3 is a right side view thereof;

FIG. 4 is a front end view thereof;

FIG. 5 is a rear end view thereof;

FIG. 6 is a top view thereof;

FIG. 7 is a bottom view thereof;

FIG. 8 is an upper perspective view showing an extendable gate for a trolley in an alternate position;

FIG. 9 is a left side view of FIG. 1 partly extended from the retracted position; and,

FIG. 10 is a left side view of FIG. 1 fully extended from the retracted position.

The broken lines in the drawings depict environment and form no part of the claimed design.
